DISCONNECTING SWITCH

Allen M. Rossman, Wilmette, Ill.

Application August 23, 1937, Serial No. 160,520

17 Claims. (Cl. 200—48)

This application is a continuation in part of my pending application, Serial No. 97,541, filed August 24, 1936, now Patent 2,218,554 dated October 22, 1940.

The present invention relates to electric disconnect switches and more particularly to air break disconnect switches as distinguished from the oil immersed type. It is one of the objects of the present invention to provide an air break disconnect switch which will be exceedingly compact and which will require a minimum amount of space for the movement of the movable contact making member from its circuit closed to its circuit open position, and which will require a minimum clearance space for the switch when the movable element thereof is in its alternate positions.

The teachings of the present invention are particularly applicable to switches for use in medium-high voltage power systems. The principles of the present invention are also particularly applicable in sub-stations, particularly sub-stations of the enclosed type. The design of air break disconnecting switches heretofore used in electric sub-stations has been such as to require a good deal of space. In accordance with the teachings of the present invention the disconnecting switch is so constructed and arranged that the blade moves in such a way as to require a minimum clearance space as it travels from its switch closing position to its switch open position. This result is accomplished by constructing the blade and part of the actuating means therefor so that the movable switch element in effect telescopes upon itself as it moves to its switch open position. Because of this switch structure it is possible to make a large part of the enclosed switchgear as a complete unit which can be shipped from the factory fully assembled.

In the preferred form of switch of the present invention the blade or contact making member is of the type which moves in a straight line between its alternate positions. The contact making member is movably mounted on a movable carriage and is so connected to the carriage that movement of the carriage in a straight line causes a like movement of the blade or contact making member at double the carriage speed. In one form of this invention the carriage comprises essentially a wheeled frame mounted on the switch supporting structure and carrying a switch blade, suitable gearing being arranged between the carriage, the stationary switch structure, and the blade so that upon movement of the carriage with respect to the stationary structure the blade moves with the carriage, and the gearing also imparts a movement to the blade with respect to the carriage so that the total movement of the blade is twice that of the carriage itself. In one embodiment of my invention

the gearing between the movable contact making member, the carriage, and the stationary portion of the switch comprises one or more rollers and means cooperating with the rollers, the blade, and the stationary structure for moving the blade with respect to the carriage in response to movement of the carriage. This means may comprise a belt looped around a wheel or pulley carried by the carriage and connected at one place to the stationary structure and at another place to the contact making structure so that upon movement of the carriage and corresponding movement of the wheel or pulley around which the laminated belt is wound, the belt moves the contact making member with respect to the carriage. The belt may comprise a stack of exceedingly thin laminations of copper strips, say each of a thickness of approximately 0.005 inch, the stack being built up to a sufficient thickness to carry the current for which the switch is designed. The laminated belt, therefore, constitutes a means for carrying the current from one stationary switch terminal to the switch blade or switch contact making member without sliding contacts so that the only sliding contact in the switch is between the movable contact making member and the stationary contact that is engaged thereby in the switch closed position. Where the current carrying capacity of the switch is so great as to require an inordinately thick stack of laminations to carry the requisite current there is provided a plurality of laminated belts, each of which carries a fraction of the total switching current, thereby maintaining the resiliency of each belt to flexing.

The rollers, which constitute a part of the gearing between the movable carriage, the stationary structure and the contact making member, also constitute the means for holding the laminated conductor that extends from the circuit to the switch blade, taut. The circuit from one switch terminal to the movable switch element is extended to the laminated belt at the point where the belt is permanently connected to the stationary structure, and thence the current divides through the belt, half of it flowing in one direction and half in the other, to the point where the belt is connected to the movable contact making member, the equal division being obtained because the two paths have substantially the same resistance and inductance.

It is another object of the present invention to provide a switch of the above mentioned character wherein most of the metal elements of the switch are of standard structural shapes so that the parts for assembling a switch can be readily obtained without the need of making special patterns, castings, or the like.

The attainment of the above and further objects of the present invention will be apparent

from the following specification taken in conjunction with the accompanying drawings forming a part thereof.

In the drawings:

Figure 1 is a longitudinal sectional view of a horizontally movable disconnect switch constructed in accordance with the teachings of the present invention, with certain of the parts broken away to illustrate the interior of the switch;

Figure 2 is a sectional view taken along the line 2—2 of Figure 1;

Figure 3 is a sectional view taken along the line 3—3 of Figure 1;

Figure 4 is a fragmentary sectional view through one of the supporting wheels of the carriage of the disconnect switch;

Figure 5 is a fragmentary view taken along the line 5—5 of Figure 4;

Figure 6 is a diagrammatic view of the switch in its open position;

Figure 7 is a diagrammatic view of the switch in its closed position;

Figure 8 is a top plan view illustrating an alternate construction, a portion thereof being omitted and other parts being broken away in order more fully to illustrate the construction;

Figure 9 is a side view of the switch shown in Figure 8, with certain of the parts omitted;

Figure 10 is a fragmentary sectional view taken along the line 10—10 of Figure 9;

Figure 11 is an enlarged fragmentary sectional view showing a portion of the movable contact making member in engagement with the stationary contact member of the switch of Figures 8 and 9;

Figures 12 and 13 are views corresponding, respectively, to Figures 8 and 9, and showing an alternate construction; and

Figure 14 is a sectional view taken along the line 14—14 of Figure 13.

Reference may now be had more particularly to Figures 1 to 7, inclusive, which illustrate one embodiment of a switch constructed in accordance with the present invention. The switch shown in Figure 1 is adapted to be mounted in a switchgear such as is shown, for instance, in my aforesaid pending application, Serial No. 97,541. The switch comprises a tubular body which extends through a hole in the wall of the switchgear and is secured to the wall of the switchgear. The switch is indicated in general by the reference numeral 1 and is adapted to extend through and be mounted on the rear wall of a bus compartment, a fragmentary portion of which rear wall is indicated at 2 in Figure 1. In one end of the tubular body of the switch is mounted a stationary contact, and in the other end is mounted a carriage that supports a movable contact that is movable horizontally within the tube into and out of engagement with the stationary contact. The outer supporting casing is cylindrical and is made of suitable insulating material. The supporting casing comprises an inner tube of insulation 3 in the forward end of which is secured a conducting bar 4 by means of suitable screws or the like 5 that terminate flush with the outer periphery of the tube 3. An intermediate tube of insulation 6 fits snugly over the tube 3 and covers the ends of the screws 5 that hold the conducting bar 4 in position. A terminal 7 is bolted to the forward end of the conducting bar 4 and is adapted to have a circuit conductor bolted or otherwise secured thereto. A movable member of copper or other high con-

ducting material in the form of a tube 10, longitudinally slit at the top, is supported within the insulating tube 3 on two pairs of rollers 11 and 12 so that the movable member 10 can ride forward and backward within the tube 3. The rear end of the movable member carries a copper ring 14 within which are bound a series of spring contact fingers 15 which are clamped in place by a ring 16. The fingers 15 constitute the female contact of the switch. The ends of the fingers 15 are pressed inwardly by coil springs 18 and 19 so that the female contact firmly grips the male contact. A plate 20 closes the forward end of the movable member 10.

A movable carriage is mounted within the movable member 10. The carriage comprises a pair of pulleys 22 and 23 secured together on their opposite sides by tie bars 24 which maintain the pulleys a fixed distance apart but permit free rotary motion of the pulleys. A laminated endless copper belt 25 is wound around the pulleys 22 and 23. The belt is made of a large number or stack of exceedingly thin laminations of copper or the like, so that the belt is exceedingly flexible. The belt is welded to the member 19 at 28 and is welded to the bar 4 at 29. The points 28 and 29 are spaced apart a distance substantially equal to half the entire length of the belt 25 so that when current flows through the belt from the point 29 to the point 28 it flows over two paths in parallel and of substantially equal resistance and inductance. The carriage, including the pulleys 22 and 23 and the tie bars 24, may be advanced or retracted by pulling on an insulating rod 30 that is connected to the forward end of the pulley tie bars 24. Belt and pulley guides 26 are secured to the tube 10 for guiding the carriage. As the carriage moves forward, the point 29 remains stationary, being welded to the stationary bar 4 and therefore the pulleys 22 and 23 roll in a counter-clockwise direction within the belt. The belt thus moves the tube 10 forward since the point 28 on the belt is welded to the tube 10. It is apparent from the construction thus far described that the speed of travel of the tube 10 will be just twice the speed of travel of the carriage within the tube. The female contact carried at one end of the tube 10 is thus moved rearwardly within the tube 3 until it engages a stationary contact 35 mounted in the rear of the tube 3. An electrical connection is thus established between the terminal 7 and the contact 35, said connection extending from the terminal 7, through the conductor bar 4, to the point 29 where the laminated belt 25 is welded to the bar 4, thence in opposite directions along the belt 25 to the point 28 where the belt is welded to the tube 10, thence by way of the tube 10, to the female contact 15, which is in engagement with the male contact 35. It is to be noted that the flexible connection between the female contact 15 and the stationary bar 4 is taut at all times, and there is no sliding connection between the female contact and the terminal 7 of the switch. In this disconnecting switch the only sliding engagement is the one between the male and female contacts. The pulleys 22 and 23 hold the belt 25 in its normal shape at all times, fix the minimum diameter around which the belt is bent or flexed, and assist in keeping the movable contact member in a straight line path of travel, and assist driving the tube 10 forward and backward.

At the rear of the bar 4 there is provided a similarly shaped bar 37 of insulation, in align-

ment with the bar 4 to guide the belt as the carriage is moved towards its "switch closed" position. Insulating tubes 39 and 40 are secured over the forward and rear ends of the outer tube 6 on opposite sides of the wall 2 of the compartment within which the switch extends. The ends of the tubes 3, 6 and 40 opposite the contact 35 are cut away, as indicated at 41, to permit inspection of the contacts when they are in engagement. A sliding tube of insulation 42 is provided at the rear end of the switch, which tube may be slipped to the right from the position shown in Figure 1 so that it covers the opening 41. When this is done the entire disconnect switch is a closed unit fully insulated and adequately protected. The only exposed live parts are the terminal 7 for receiving one line connection and a stud 44 for receiving another line connection. If any one of the laminations of the belt 25 should break, there is no possible danger that it will extend beyond the female contact in a direction towards the male contact, since the rear end of the carriage is entirely closed by the closures 14 and 20. By reason of the two insulating tubes 3 and 6, instead of a single tube of their combined thickness, the heads of the screws 5 are covered by the insulating tube 6 so that the creepage distance from the screws to the grounded supporting frame 2 which surrounds the tube 6 is very greatly increased.

Reference may now be had more particularly to the switch shown in Figures 8, 9 and 10. This switch comprises a grounded metal mounting base 50 at one end of which is rigidly mounted an insulator 51 that supports the stationary switch contact, and at the other end of which is mounted a rotary insulator 52 and a stationary insulator 53 which support the contact switch blade for the movable contact making member of the switch. The insulator 52 is mounted upon the base 50 by means of a suitable bearing, the spindle of which supports the insulator and extends through the base 50 where it is connected to a crank 54 whereby the insulator 52 may be rotated in a manner well known in the switching art. The tops of the insulators 52 and 53 are joined together by a bracing member 55, preferably of non-magnetic material, which is rigidly bolted to the insulator 53 and which is connected to the insulator 52 by means of a suitable bearing 56 (Fig. 10). A crank 58 is rigidly secured to the insulator 52 so that upon rotation of the insulator the crank arm is also rotated. The bracing member 55 supports a pair of longitudinally extending inwardly facing channel shaped side rails 60 and 61 of non-magnetic material. A carriage 62 is mounted between the side rails 60 and 61 and supports the switch blade 63, which blade is movable with respect to the carriage. The carriage comprises an upper horizontal plate 65 and a lower horizontal plate 66 each of substantially a rectangular shape and preferably of non-magnetic material. The plates 65 and 66 carry four wheels or pulleys 68, 69, 70 and 71, which are spaced from the plates by suitable spacers 72 and are freely rotatable about their respective axes. The switch blade or contact making member comprises two parallel outwardly facing non-magnetic channel members 74 and 75 secured together in spaced relationship by a pair of spacers 76 and 77. The circuit is extended from the stationary terminal of the switch by means of two stacks of exceedingly thin laminations of copper or the like, indicated at 80 and 81, which extend on the outsides of the

channels 60 and 61 to approximately the mid points of the channels. The laminated stack 80 extends through a slot in the web of the channel 60 to the inside of the channel where the stack is divided in two, half of the laminations then extending, as indicated at 83, around the pulley 69 thence along the inside of the channel 74 to a slot 85 where the laminations 83 extend through the channel 74 to the outside of the web of the channel. The other set of laminations of the stack 80, indicated at 86, extends around the pulley 71, thence along the inside of the channel 74 to the slot 85 of the channel, where that group of laminations extends through the channel 74 and is joined with the group of laminations 83. The laminated conductor 81 likewise extends along the outside of the channel 61 to an opening 87 in the channel, thence through that opening, where the group of laminations is divided, half of the laminations extending at 88 along the inside of the channel 61, thence around the pulley 68 and along the inside of the channel 75 to an opening or slot 89, where it extends through the web of the channel 75. The other half of the laminations of the stack 81 extend through the opening 87, around the pulley 70, thence along the inside of the channel 75, as indicated at 90, to the opening 89, where they join with the group of laminations 83. The laminated conductor 92, which is a consolidation and continuation of the laminated conductors 80 and 81, or a consolidation of the two laminated belts around the sets of pulleys 68-70 and 69-71, extends between the two channel members 74-75 for the full length of the switch blade. At the forward end of the blade the mass of laminations is again divided, half of the group being indicated at 95 and the other half at 96. The slots 87 and 89 are so located with respect to one another that the length of the laminations 88 between the slots and around the pulley 68 is substantially equal to the length 90 around the pulley 70. The same is true of the laminations extending around the pulleys 69 and 71. The belts or loops of laminations around the pulleys are maintained taut by the pulleys. The pulleys 68 and 70 ride between the flanges of the channels 61 and 75, and the pulleys 69 and 71 ride between the flanges of the channels 60 and 74. The carriage 62 is thus supported from the flanges of the channels 60 and 61 by the pulleys, and the pulleys in turn support the switch blade 63. The carriage is free to roll between the flanges of the channels 60 and 61 and is moved forward and backward by means of the crank 58 which is connected to the carriage by a link 93. In its rolling movement it imparts motion to the switch blade in a manner similar to that of the switch of Figure 1, previously set forth. The forward end of the blade has a contact making portion formed thereon for establishing circuit connections with the stationary contact of the switch. The U-shaped spacer 77 includes a portion 94 interposed between the groups of laminations 95 and 96 to keep them spread apart. The laminations are maintained spread apart by a series of springs 97 so that they bear against the inside of a keeper 98 that is secured to the forward end of the switch blade, the groups of laminations 95-96 being free to move away from the keeper, that is, towards one another, against the action of the springs 97. Each group of laminations 95 and 96 has a number of contact making studs 99 secured thereto, in this instance sixteen studs for each group of lamination.

tions, as may be seen from Figure 9, the studs being arranged in horizontally extending rows vertically spaced from one another. The stacks of laminations 95 and 96 are slit between the rows of studs, as indicated at 100, to improve the resiliency of the stacks.

Each of the contact studs is secured to the laminations in a manner illustrated more fully in Figure 11. For that purpose the group of laminations 96 are clamped together and drilled and tapped to receive the threaded end of a contact stud 99. The stack of laminations is then heated adjacent the tapped hole and the threads are then tinned. While the stack of laminations is still hot and the tin still plastic, the stud 99 is threaded through the treads in the tapped hole in the stack of laminations 96 so that it extends through the stack of laminations, as illustrated in Figure 11. Thereafter upon cooling of the tin or solder, a firm electrical engagement is had between the stack of laminations and the contact stud 99. Each stud 99 extends freely through an oversized hole in the keeper 98. The springs 97 maintain the stacks of laminations and the contact studs in their extreme outer position with respect to the keeper 98. When the blade is moved into engagement with the stationary contact member, the studs 99 are forced inwardly a small amount, and the springs 97 maintain a firm electrical engagement between the contact studs and the stationary contact. The contact making ends of the studs 99 are silver plated to increase the conductivity between the studs and the stationary switch contact.

The stationary contact of the switch is indicated at 101 and comprises two prongs outwardly flared at their end to receive the contact studs 99. As the switch is actuated to its closed position, in a manner to be presently set forth, the contact studs move between the prongs of the stationary contact 101 and are forced inwardly a slight amount against the action of the springs 97. Each pair of contact studs has an individual spring 97, there being sixteen such springs in the switch illustrated in Figures 8 and 9, so that each spring maintains its individual pressure against the associated pair of contact studs and thereby maintains the associated pair of contact studs in firm pressure engagement with the stationary contact member. Due to the extreme resiliency and flexibility of the stacks of laminations 95-96 there is sufficient give or flexibility in the stack of laminations between adjacent contact studs to permit each spring 97 to force its associated contact studs into firm pressure engagement with the stationary contact 101, without regard to the action of any of the other contact studs.

An explanation will now be given of the mode of operation of the switch illustrated in Figures 8, 9 and 10. Upon rotation of the insulator 52 by turning of the crank 54, the crank 58 is turned, thereby actuating the link 93 to move the carriage 62 rearwardly between the channel frame 60-61. The four rollers or pulleys 68-71 thus ride in the channels and cause the two belts to roll and thereby impart longitudinal motion to the switch blade 63, the blade moving at twice the speed of the carriage, and thereby moving exactly twice the distance that the carriage moves. When the contact making structure engages the prongs of the contact 101 each of the contact studs 99 is moved inwardly a small

amount by the prongs 101 against the pressure of the springs 97 as previously set forth, and the contact studs thereby establish firm pressure engagement with the prongs 101. The switch opening movement is exactly the reverse of the switch closing movement above set forth, as will be apparent from the description thus far given.

Reference may now be had more particularly to the switch shown in Figs. 12, 13 and 14. Here, as in the switch of Figure 9, there is provided a grounded base 50, a stationary contact supporting insulator 51 and a pair of insulators 52 and 53 for supporting and actuating the movable contact making member, of which the insulator 52 is mounted for axial rotation by means of a crank 54, as in the switch of Figure 9 previously described. The switch of Figure 13 is of lesser width than in the switch of Figure 9. The rotary insulator 52 and the stationary insulator 53 are joined by a bracing plate 120 which is rigidly bolted to the insulator 53 and which is connected to the insulator 52 by means of a bearing, like the bearing 56 of Figure 10, whereby the insulator 52 may rotate axially with respect to the bracing plate 120. The bracing plate 120 has a vertical plate 121 bolted or otherwise rigidly secured to the plate 120 at one longitudinal edge thereof, as is apparent from Figures 12 and 14. An inwardly facing longitudinally extending channel bar 123 is suitably bolted to the plate 121 adjacent the top thereof. The channel 123 constitutes a guideway for one side of a laminated conducting belt, to be hereafter described, and also a support for one side of the movable carriage. Along its forward edge the bracing plate 120 has a plurality, in this instance three, of standards 125 secured thereto, each of which standards supports a roller 126 at its upper end, the rollers being swiveled to turn freely about their axes on the standards 125.

The blade actuating carriage is indicated at 130 and comprises upper and lower horizontal longitudinally extending bars 131 and 132 that support pulleys or rollers 134 and 135. The switch blade or element which carries the contact making structure comprises an I-beam 138. The rollers 134 and 135 ride between the flanges 50 of the channel 123 and between the inwardly directed flanges of the I-beam 138. The rollers 126 ride between the outwardly directed flanges of the I-beam 138.

A laminated copper conductor 140, consisting of exceedingly thin continuous strips of copper each of a thickness of about 0.005 inch, is secured to the outside of the plate 121 and extends through a slot 142 in the plate 121 and in the channel 123, to the inside of the channel where it is divided in two. Half of the laminations, indicated at 143, pass rearwardly in the trough of the channel 123 and around the pulley 134, while the other half 144, extend forwardly in the trough of the channel 123 and around the pulley 135, thence the two groups of laminations 143 and 144 extend in the inner trough of the I-beam 138 to a slot 147. Here the groups of laminations are again joined and then they extend together forwardly, within the outer trough of the I-beam 138, as indicated at 148, to a contact making head 149 that is secured to the forward end of the I-beam 138. The rollers 126 press the stack of laminations 148 firmly against the I-beam 138. A female contact making member 150

is secured to the forward end of the contact making head 149 and in good electric engagement with the end of the stack of laminations 148. The female contact making member cooperates with a male or stationary contact 151 that is mounted on the stationary insulator 51 and in proper conductive relationship to a bus 152 or other suitable switch terminal.

The switch is actuated by means of a spur gear 155 that is rotated by rotation of the insulator 52, said gear being rigidly secured to a spindle carried by the head of the insulator 52 and extending through a suitable rotary bearing in the manner illustrated in Fig. 10, for example. The gear 155 meshes with a similar gear 156 carried on the bracing plate 129. A crank arm 157 is secured to the gear 155 and is rotated thereby, the crank arm actuating a link 158 which is pivoted at one end to the crank arm and at its opposite end to the bar 132 of the carriage 130.

The operation of the switch is as follows: Upon rotation of the insulator 52 by the crank 54 the gear 155 turns the gear 156, which turns the crank 157 to actuate the link 158 to move the carriage 130 forward. As the carriage moves forward, the rollers 134 and 135 are moved forward bodily and thus rotate in a direction counter-clockwise as seen in Figure 12, so that the roller 134 rolls forward on the belt 143 while the roller 135 rolls forward on the belt portion 144 and move the top portion 144 progressively further forward in the channel 123. The belt 143 thus rolls in the trough of the channel 123, the portion of the belt at 142 remaining stationary. This forward rolling movement of the belt causes the I-beam or blade structure 138 to move forward at a speed which is twice the speed of the carriage 130, and a distance which is twice the distance of travel of the carriage 130. During this movement the belt or loop formed by the conductor portions 143-144 is kept taut, and the rollers 126 maintain the laminated conductor 148 in the outwardly facing channel of the I-beam 138. The contact 150 is thus moved into engagement with the contact 151, the distance of movement of the contact-making member 150 being twice the distance of movement of the carriage 130.

The gears 155 and 156 are introduced in order to permit the use of a longer crank arm 157, without increasing the width of the structure. If a shorter crank arm were used, then the movement imparted thereby to the link 158 would be insufficient to move the contact making member the requisite distance. The gears 155 and 156 are not necessary in the structure of Figure 10 because in this structure the switch is of appreciably greater width, thereby allowing the use of a longer actuating crank on the head of the insulator 52, without increasing the overall width of the switch.

In the switches of Figures 9 and 13, all of the operating structure above the link 93 or the link 158, is preferably of non-magnetic material. The parts of the switches on which the belts of laminated strips roll, namely the channels 60-60 and the channels 74-75 of the switch of Figures 8-11, and the channel 123 and the I-beam 138 of the switch of Figures 12-14 are preferably made of insulating material to prevent the division of current therethrough and confine all the current to the laminated conductor. If those parts are made of conducting material (non-magnetic) an insulating strip of "bakelite" or the like 75

is preferably interposed between the laminated conductor and the inside of the channels in which the laminated conductor rolls. This is desirable to prevent the flow of large currents between the belt and the supporting channels, as during short circuit conditions, for such large currents may cause the laminations to become welded to the channels, or welded together.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. An electric switch including a member mounted for rectilinear movement, a contact making member associated with the first member and movable therewith, means responsive to movement of the first member for moving the contact making member rectilinearly with respect to the first member in the direction of movement of the first member whereby the speed of the contact making member is the sum of its speed with respect to the first member plus the speed of the first member itself, said means including gearing one part of which is carried by the first mentioned member and is rotated by rectilinear movement thereof, and a driving connection between said rotated part and the contact making member, said driving connection including a flexible conductor looped over said rotated part and mechanically connecting the contact making member with a stationary portion of the switch.

2. An electric switch including a member mounted for rectilinear movement, a contact making member associated with the first member and movable therewith, means responsive to movement of the first member for moving the contact making member rectilinearly with respect to the first member in the direction of movement of the first member whereby the speed of the contact making member is the sum of its speed with respect to the first member plus the speed of the first member itself, said means including gearing one part of which is carried by the first mentioned member and is rotated by rectilinear movement thereof, and a driving connection between said rotated part and the contact making member, said driving connection including a flexible belt of conducting material looped over said rotated part, means for keeping the loop taut, a mechanical and electrical connection between one part of the belt and the contact making member, means holding another part of the belt stationary, said two parts of the belt being 180° apart on said looped belt.

3. An electric switch including a pair of switch terminals and a contact making member movable into and out of circuit establishing connection between them, an electric connection between one of the terminals and the member comprising a pair of spaced wheels and a flexible copper belt tautly looped over the wheels, one point on the belt being secured to said one of the terminals and another point being secured to the contact making member.

4. An electric switch including a pair of switch terminals and a contact making member movable into and out of circuit establishing connection between them, an electric connection between one of the terminals and the member comprising a pair of spaced wheels and a flexible

copper belt tautly looped over the wheels, one point on the belt being secured to said one of the terminals and another point being secured to the contact making member, the two points being spaced from one another half the distance around the belt.

5. An electric switch including a supporting structure, a contact making member supported thereon and movable in a straight line from its switch open position to its switch closed position, a flexible conductor secured to the supporting structure and to the member, and means for maintaining the conductor taut in every position of the member from its open to its closed positions, said means comprising a pulley around which the conductor is looped a fraction of a turn, said pulley having rolling movement along the supporting structure.

6. An electric switch including a stationary structure, a switch terminal carried thereby, a flexible conductor in the form of a closed loop secured at one point to the stationary structure and capable of rolling with respect to said structure while maintaining said one point fixed with respect to the structure, a contact making member movable in a straight line, another point on said loop being fixed to the contact making member, and means for holding the loop taut whereby the contact making member is actuated by the loop as the loop is rolled with respect to the stationary structure.

7. An electric switch including a stationary structure, a switch terminal carried thereby, a flexible conductor in the form of a closed loop secured at one point to the stationary structure and capable of rolling with respect to said structure while maintaining said one point fixed with respect to the structure, a contact making member movable in a straight line, another point on said loop being fixed to the contact making member, and means for holding the loop taut whereby the contact making member is actuated by the loop as the loop is rolled with respect to the stationary structure the two points on the loop being so spaced from one another as to divide the loop into two parts having like electrical characteristics.

8. An electric disconnect switch comprising a supporting structure, a carriage mounted for rectilinear movement in said structure, a contact making member carried by said carriage and movable thereby, means for moving the carriage, and means responsive to the movement of the carriage for moving the contact making member at a speed with respect to the carriage which is at least equal to the speed of the carriage with respect to the supporting structure, and in the same direction, so that the contact making member moves at least twice as far as the carriage.

9. In an electric disconnect switch, a movable carriage, rollers for guiding the carriage secured thereto on opposite sides thereof, the rollers on opposite sides of the carriage lying in substantially the same plane, and a contact making member carried by the carriage and guided between said rollers.

10. In an electric disconnect switch, a movable carriage, rollers for guiding the carriage secured thereto on opposite sides thereof, the rollers on opposite sides of the carriage lying in substantially the same plane, a contact making member

carried by the carriage and guided between said rollers, and means for moving the contact making member with respect to the carriage, said means including at least one of said rollers.

5 11. An electric switch including a switch terminal, a contact making member movable relative thereto, a flexible conductor connecting the two, and means for maintaining the conductor taut as the contact making member moves, said means comprising a rotatable pulley movable axially with respect to the terminal and with respect to the contact making member, said conductor being looped around the pulley and means confining the axial movement of the pulley to a path parallel with the path of movement of the contact making member during a substantial part of the operative movement of the same.

12. A switching member comprising a flexible stack of conducting laminations, a plurality of contact studs extending through the stack, a metal bond between each stud and the individual laminae of the stack, the stack being flexible between adjacent studs, and separate spring backing means for the respective studs, to permit individual angular movement of the respective studs.

13. A switch contacting member comprising a flexible stack of laminations, rows of contact studs extending through the stack at one end thereof, and a relatively rigid member extending along an end lamina, the studs passing loosely through holes in the member.

14. A switch contacting member comprising a flexible stack of laminations, rows of contact studs extending through the stack at one end thereof, the stack being slit between adjacent rows of studs to permit individual relative movement of the respective studs, and means inhibiting excessive relative movement of the studs.

15. A switching member comprising a stack of laminations of conducting metal, a plurality of side by side spaced contact studs secured to the stack, and individual pressure exerting springs for the respective studs, said stack of laminations being sufficiently flexible between adjacent contact studs to permit relative movement of the studs by the respective springs.

16. A switching member comprising two side by side spaced groups of flexible stacks of laminations of conducting metal, a plurality of adjacent contact studs secured to each stack, springs between the stacks urging the stacks apart, means limiting the spreading of the stacks, said studs extending through said limiting means and movable therethrough against the action of springs.

17. Switching means comprising a contact, a laminated contact making member movable into the contact and having a plurality of studs projecting from each of the opposite sides thereof into engagement with the contact, the studs being in relatively movable pairs with one stud of each pair projecting from one side of the contact making member and the other stud of each pair projecting from the other side of the contact making member, the studs of each pair being relatively movable, and a separate spring associated with each pair of studs and urging them outwardly of the contact making member.
